UNITED STATES PATENT OFFICE.

MILTON H. SPIELMAN, OF CLEVELAND, OHIO, ASSIGNEE TO THE DOMESTIC ELECTRIC COMPANY, OF CLEVELAND, OHIO, A CORPORATION OF OHIO.

VACUUM CLEANER.

Application filed September 29, 1922. Serial No. 591,243.

This invention is concerned with vacuum cleaners and has for its general object the provision of a simple, compact, efficient, electrically driven vacuum cleaner adapted to be supported in the hand and applied to various objects to be cleaned. The proportioning and arrangement of the various parts of the device relative to the nozzle is such that the cleaner may be provided with a short handle to permit the ready and dexterous manipulation thereof by the operator.

A further object of the present invention is the provision of a vacuum cleaner construction which will permit the carrying out of the foregoing object and wherein the fan motor is completely encased by a metallic housing rigidly secured to the frame of the cleaner whereby a filtering bag may be removably attached to the frame completely surrounding the motor housing. The character of the housing is such as to protect the motor from dust and dirt particles collected by the bag while causing the circulating air currents within the bag to cool the housing and motor.

Other objects will be hereinafter set forth in the following description of the accompanying drawings which embody a preferred form of my invention. The essential characteristics will be summarized in the claims.

In the drawings, Fig. 1 is a side elevation of a vacuum cleaner embodying my invention; Fig. 2 is a plan view of the cleaner with the motor housing and filtering bag removed; Fig. 3 is an enlarged cross sectional elevation taken substantially along the line 3—3 of Fig. 2 and showing the relation of the motor housing, fan casing and nozzle of the device; Fig. 4 is a plan view of the motor housing; Fig. 5 is a transverse sectional view taken through the nozzle and brush substantially along the line 5—5 of Fig. 2.

In carrying out the objects of my invention, I provide a frame 10 preferably comprising an aluminum casting and forming a nozzle portion 11, a suction chamber or fan casing 12 and a motor housing support 13 provided with an annular grooved flange 14 affording removable attachment for a filter bag 15. As shown in Fig. 3, the bag 15 completely surrounds an upwardly extending motor housing 16 attached to the

upper portion of the frame 10, and secured in place by screw member 17.

The lower portion of the frame 10 is formed to provide an offset depending nozzle in the manner illustrated in Figs. 1, 2 and 3; the shape of the nozzle being such as to provide an elongated rectangular nozzle opening 18. A rigid handle 20 may be secured to a suitable extension 21 of the frame in any convenient manner such as a screw 22 passing through the extension 21 and the bifurcated lower end of the handle 20. The handle 20 is preferably hollow to afford protection for lead wires 24 which extend longitudinally of the handle and upwardly through the frame and motor housing. It will be noted that I have arranged the handle below the center of gravity of the cleaner and in such relation to the nozzle opening that the center line of the handle lies in a median plane passing through the nozzle. This arrangement greatly facilitates the ready manipulation of the device by the operator.

I prefer to suspend a brush 25 in the nozzle with the lower ends of the bristles 26 extending slightly from the nozzle opening as shown in Fig. 5. This brush may be mounted in the frame in any suitable manner. A convenient way is to shape one end 27 of the back of the brush to fit a slot 28 formed interiorly of the end wall of the nozzle, the other end of the brush being held in clamped relation to the frame by a small screw 28.

The nozzle portion of the frame merges into a bottom or partition wall 30 which divides the interior of the frame into nozzle and fan chambers.

An annular wall 31 extends from the bottom 30 upwardly a sufficient distance to provide a sufficient height in the fan chamber 12 to afford space for a suction fan 40 mounted on a shaft 48 of the motor 44. The upper wall of the fan chamber is formed by an inwardly extending flange 35 upon which a flange 16^a of the motor housing 16 rests, so that the upper wall of the fan chamber is formed by the frame flange 35, the motor housing flange 16^a and a fan web 41 or disc 41 from which the fan blades 42 depend. The circumference of the fan web 41 may be accurately machined whereby it may be rotated in close relation to a correspondingly relieved or bored depending 110

flange 43 integral with the motor housing to prevent the ingress of dust or other extraneous matter to the motor parts. The upper end of the motor is completely enclosed by an end member 45 comprising a shaft bearing and brush carrier.

The movement of the air is as follows:—
The air is drawn through the nozzle opening 18 upwardly to an opening 30^a formed 10 in the bottom wall 30 of the fan chamber and is forced from the fan chamber upwardly through an opening 46, which is provided by omitting a portion of the frame flange 35 and motor housing flange 16^a as illustrated in Figs. 2 and 4 respectively, into the filtering bag 15. The position of the shaft of the motor and the fan relative to the opening 30^a is such, that the center of the shaft is substantially coincident with the center of 20 the opening 30^a. As shown in Fig. 3, the proportioning of the nozzle portion of the frame 10 and the fan chamber walls is such that the motor is supported with the motor shaft slightly inclined to the plane of the 25 nozzle opening; the purpose of this arrangement being to properly balance the weight of the entire device relative to the handle 20 and the nozzle, whereby the operator or user may dexterously manipulate the cleaner 30 when applying the nozzle to various objects, such as upholstered furniture, clothing and the like. It is to be understood however, that this result may be obtained in a variety of convenient arrangements which would 35 come within the scope of my invention.

The filtering bag 15 may be secured to the cleaner frame in any suitable manner. I have found however, that a very efficient and convenient way of removably attaching 40 the bag to the cleaner is to provide a gathering cord 50 which may be strung through a lower hemmed end 15^a of the bag to permit the drawing or gathering of the open end, of the bag upon the grooved flange 14 of the 45 frame, the groove 14^a being of sufficient size to receive the gathered edge of the bag and thus prevent its being forced away from the frame when inflated.

It will be noted that I have affixed the 50 handle to the frame in such relation to the nozzle opening that the center line of the handle will lie in a medium plane passing through the nozzle. This arrangement 55 greatly facilitates the easy manipulation of the device by the operator.

A hand applied vacuum cleaner constructed in accordance with the foregoing description will be found to have many advantages both in the manufacture and in the use 60 thereof. The novel arrangement of the motor housing upon the frame of the device whereby the motor is disposed within the filtering bag affords a very compact construction which permits such arranging of 65 the nozzle relative to the handle so that the

weight of the device may be properly balanced relative to the handle.

A further advantage of this arrangement is that the elongated nozzle opening may be efficiently used as it extends in a common direction with the handle whence the nozzle may be readily manipulated in all directions; the nozzle at no time being obscured from the vision of the user. The provision of the motor with a dust-proof frame or housing whereby it may be disposed within the filtering bag has the further advantage in that the air forced into the filtering bag circulates about the housing and serves as a motor cooling medium. If desired, the motor housing frame may comprise aluminum castings to further decrease the weight of the device.

The removal of dust and other extraneous matter from the cleaner is effected in a very simple manner by simply loosening the gathering cord and removing the bag from the cleaner; the heavier dirt not adhering to the bag having gathered between the flange 14 and the motor housing may be removed by simply inverting the device and shaking it.

I claim:—

1. In a vacuum cleaner, the combination of a frame member comprising a fan housing portion with a closed circular periphery and a nozzle portion having an elongated rectangular opening, the nozzle portion depending below the fan housing portion, a handle rigidly secured to the nozzle portion of the frame and extending in a plane longitudinally bisecting the nozzle opening, a brush rigidly mounted within the opening and extending to the mouth thereof, a suction fan suspended within the fan housing, a motor therefor, a motor housing completely enclosing the motor, said motor housing being mounted on the frame in such a manner that the axis of the motor shaft lies in said plane and a filtering bag completely surrounding the motor housing and detachably secured to the frame.

2. In a suction cleaner, a frame member comprising a nozzle portion, and a fan housing portion, an annular flange extending upwardly from the fan housing portion a filtering bag attached to said flange, a fan disposed within the fan housing, an inwardly extending flange forming an incomplete annulus and rigid with the frame, the opening in said last named flange forming an air passage between the fan housing and the bag, a motor for the fan, and a motor housing secured to the inwardly extending flange and substantially covered by the filtering bag.

3. In a vacuum cleaner of the character described, the combination of a frame having a nozzle portion depending from an annular fan housing portion and having a rectangular opening, said frame having a par-

- titioning wall between the nozzle portion and the fan housing portion provided with a centrally disposed opening, a fan, a radial flange formed to extend inwardly in the 5 annular portion and spaced apart from said partitioning wall a distance slightly greater than the width of the fan, a motor, a housing therefor completely enclosing the motor, the housing being provided at the fan end 10 thereof with a flanged portion adapted to engage the annular flange of the casing, a second annular flange extending upwardly from the first named flange, and a filtering bag removably secured to said last named 15 flange.
4. In a vacuum cleaner the combination of a frame having a nozzle portion with a rectangular opening and a cylindrical fan casing portion, a partitioning wall between 20 said portions provided with a centrally disposed opening, a fan positioned therein with the axis thereof extending in a plane longitudinally bisecting said openings, a motor for driving the fan, a motor housing completely enclosing the motor, the fan being 25 webbed to comprise closure means for one end of the housing, a radial flange extending inwardly in the fan casing portion com-
- prising a supporting means for the motor housing, said fan casing being of greater diameter than the motor housing whereby an air passageway is provided from the fan casing exteriorly of the motor housing. 30
5. In a vacuum cleaner of the character described, the combination of a frame comprising a nozzle portion and an annular fan housing portion, a partitioning wall between said portions, said partitioning wall having a centrally disposed opening relative to the annular portion, the nozzle portion being 35 offset relative to the annular portion, said centrally disposed opening being at one end of the nozzle portion, the annular portion being provided with an inwardly extending flange, the relation of the nozzle and flange 40 being such that the plane of the nozzle opening and the plane of said flange converge whereby a motor housing may be mounted upon the flange with the center line of the motor lying in a plane which bisects the annular portion and the nozzle portion the center line being disposed at an angle relative to the mouth of the nozzle. 45

In testimony whereof, I hereunto affix my signature.

MILTON H. SPIELMAN
